(57) **CLAIM**

The ornamental design for an electronic scale set, as shown and described.

DESCRIPTION

FIG. 1 is the combined state diagram of its top view of an electronic scale set, showing my new design;

FIG. 2 is the combined state diagram of its bottom view thereof;

FIG. 3 is a top perspective view thereof of component 1;

FIG. 4 is a bottom perspective view thereof of component 1;

FIG. 5 is a front view thereof of component 1;

FIG. 6 is a rear view thereof of component 1;

FIG. 7 is a left side view thereof of component 1;

FIG. 8 is a right side view thereof of component 1;

FIG. 9 is a top view thereof of component 1;

FIG. 10 is a bottom view thereof of component 1;

FIG. 11 is a top perspective view thereof of component 2;

FIG. 12 is a bottom perspective view thereof of component 2;

FIG. 13 is a front view thereof of component 2;

FIG. 14 is a rear view thereof of component 2;

FIG. 15 is a left side view thereof of component 2;

FIG. 16 is a right side view thereof of component 2;

FIG. 17 is a top view thereof of component 2; and,

FIG. 18 is a bottom view thereof of component 2.

The broken lines in the drawings illustrate the portions of the electronic scale set, which form no part of the claimed design.

1 Claim, 18 Drawing Sheets
